UNITED STATES PATENT OFFICE.

EDWARD J. PENNINGTON, OF LONDON, ENGLAND, ASSIGNOR OF ONE-HALF
TO J. W. PLANK AND GEORGE EDWARD MILLS, OF CARLISLE, PENN-
SYLVANIA.

CONDENSER FOR AUTOMOBILES.

SPECIFICATION forming part of Letters Patent No. 696,478, dated April 1, 1902.

Application filed June 22, 1901. Serial No. 65,723. (No model.)

To all whom it may concern:

Be it known that I, EDWARD J. PENNINGTON, a citizen of the United States, residing at the Hotel Metropole, London, England, have 5 invented new and useful Improvements in Devices for Effecting the Condensation of Exhaust - Steam on Steam Road - Vehicles, of which the following is a specification.

My invention consists of a device for condensation of exhaust-steam on steam road-vehicles and either so reducing the temperature as to allow of its final escape in a practically invisible and noiseless condition or returning it as water to either the reservoir or direct to 15 the boiler.

In the accompanying drawings, Figures 1 and 2 are views showing one form of my invention. Fig. 3 shows the invention in modified form. Figs. 4 and 5 illustrate further 20 modifications. Fig. 6 shows a special adaptation and embodiment of my invention.

Similar numerals of reference indicate similar parts in the respective figures.

Referring more especially to Figs. 1 and 2, the exhaust-steam is carried by a pipe 1 from the engine to a chamber 2 in the hub of the wheel of the vehicle. Into this chamber 2 are screwed or otherwise fastened the spokes 4 of the wheel, which are made of steel tubes, 25 with the ends opening into the chamber 2, and at the end of the spokes, near the rim of the wheel, are holes 5, through which the steam, now condensed into water by the centrifugal force with which it has been thrown, (a force 30 which compels the steam to travel at a higher speed than the normal rate of expansion in its then-attenuated form,) is allowed to escape. The hollow spokes thus form a condenser which is traveling in two directions—around 35 its own axis and also in the direction the vehicle is traveling—and consequently it is always in contact with a cool atmosphere. Additional cooling effect can be secured either by placing around the spokes disks 6 to act 40 as radiators or by attaching ribs 7 down the sides of the spokes.

Referring now to Fig. 3, when it is desired to condense the steam and save water to use it again through the boiler, I employ two 45 low chambers 2 in the hub, the first one, 2,

to receive the exhaust-steam, as already described, which steam is thrown by centrifugal force through the hollow spokes, and instead of being allowed to escape near the rim of the wheel it continues to travel along the hollow 55 spokes, each of which has a U-shaped bend 4^a, where it is passed through a specially-constructed rim (see Fig. 3) and runs back to the second chamber of the hub. When the steam, now converted into water, reaches said sec- 60 ond chamber, it is withdrawn by a pump and carried to either the cistern or to the boiler by means hereinafter described.

Having reference now to Figs. 4 and 5, instead of using hollow spokes for the condensation of steam I pass the exhaust-steam from the first chamber 2 into a pipe 1^a, the end of which is inserted in said chamber, and the pipe is then run around spirally in gradually-increasing folds, as shown, being made fast 70 to and laid up flat against the spokes 4 until the spirally-coiled pipe reaches the inner circumference of the rim, when if it is not desired to finally return the condensed steam 75 to the boiler or reservoir it is allowed to escape as water, which it will of course do when the open end of the pipe lying against the rim is near the ground. If, however, the condensed steam is to be returned as hot water 80 to the boiler or reservoir, the pipe when it has filled all the space with its coils between the chamber and the rim is bent sharply around (see particularly Fig. 5) and rewound in gradually-decreasing coils on the other 85 side of the spokes until the last and inner coil reaches the second chamber 2^a in the hub already referred to, the end of the pipe terminating in said chamber and discharging the hot water therein. The hot water is ex- 90 tracted from the chamber 2^a by means of a pump through a flexible or other pipe having a connection with the chamber 2^a. The spirally-coiled pipe 1^a may be placed between the spokes of the wheel when such spokes are 95 staggered, and the spokes would then act as a fan driving a current of air on the coiled pipe, helping to fan and cool the coil and assist condensation.

I have yet to show how I introduce the ex- 100

haust-steam into the first chamber 2 in the hub and finally attach the pump to extract the water from the second chamber 2^a, and I will illustrate this on an axle 10 of a wheel 5 which is a fixed axle, the wheel revolving around it, having special reference to Fig. 6. The axle 10 is preferably of tubular steel, and into the wall of the tubular axle at a suitable place I tap and screw in a nipple 11—say 10 about the middle of the axle—to which nipple is attached the exhaust-steam pipe 1 from the engine. The exhaust-steam may travel to the end of the axle, as both wheels are fitted with similar condensing apparatus. The 15 outer wall of the chamber 2 on the inside of the wheel has a bearing on the axle. The length of the axle within the chamber 2 is, say, two inches, when a division-wall, which also has a bearing on the axle, is met. Be- 20 yond the division-wall is the second chamber 2^a, two inches wide, measuring along the axle, when the outer wall on the side of the wheel farthest from the carriage is met, with its bearing-surface on the axle, through and be- 25 yond which the axle end protrudes in order to receive a nut 12 or other device for preventing the wheel coming off and to allow of the attachment of flexible or other tubing 13, with which the pump 14, drawing the water 30 formed by the condensed steam, is connected. The hub, as stated, consists of two chambers, with a division-wall between them, the three walls being of sufficient thickness and strength to afford bearing-surface for the axle in case 35 of a free wheel or of keying-surface for a wheel fixed to a revolving axle. The axle is slotted or perforated on the length which is contained within the two chambers, the inner slots being to admit the steam from the hollow axle to the 40 first chamber for circulation through either the spokes or the spirally-coiled tubes, the outer slots on the axle being to admit the suction of the condensed water by the pump from the second chamber into the axle, which water 45 is afterward delivered by the pipe connection from one end of the axle to the reservoir or the boiler. A tubular axle is corked up at a point opposite the division-wall 2^b in the hub, so that the steam cannot mix with the water

without first pressing through the spokes 4 50 or spirally-coiled tubes 1^a. In case of a wheel keyed to an axle and revolving with it the axle is hollow, with perforations at parts passing through the chambers, as before described, the only difference being in style of steam 55 and water joints for admitting steam and drawing off water, which are of suitable design and for which no claim of novelty is made.

I claim—

1. In a device for effecting the condensation of exhaust-steam on steam road-vehicles, the combination with the steam-exhaust pipe, of a wheel, which is one of the running-wheels of the vehicle, said wheels having a chambered hub to receive the exhaust, and radially-arranged distributing-pipes leading from the chambered hub, said pipes being provided with discharge-openings near the rim, substantially as set forth. 60

2. In a device for effecting the condensation of exhaust-steam on steam road-vehicles, the combination with the steam-exhaust pipe, of a wheel which is one of the running-wheels of the vehicle, said wheel having a chambered hub to receive the exhaust, and radial hollow spokes extending from the chambered hub to the rim, said spokes being provided with discharge-openings near the rim, substantially 70 as set forth. 75

3. In a device for effecting the condensation of exhaust-steam on road-vehicles, the combination with the steam-exhaust pipe of a chambered wheel, which is one of the running-wheels of the vehicle, a hollow axle upon which 85 said wheel is mounted, there being communication between said chambered wheel and the interior of said axle, said wheel being provided with means for receiving, distributing and discharging the exhaust, substantially as set 90 forth. 80

In testimony whereof I affix my signature in presence of two witnesses.

EDWARD J. PENNINGTON.
